UNITED STATES PATENT OFFICE

127,626

DESIGN FOR A RELIGIOUS SHRINE

Arthur Valliere, Newtonville, Mass.

Application January 18, 1941, Serial No. 93,185

Term of patent 7 years

To all whom it may concern:

Be it known that I, Arthur Valliere, a citizen of the United States and resident of Newtonville, county of Middlesex and State of Massachusetts, have invented a new, original, and ornamental Design for a Religious Shrine, of which the following is a specification, reference being had to the accompanying drawings, forming a part thereof.

Fig. 1 is a front view of the religious shrine constituting the subject matter of this application.

Fig. 2 is a plan view thereof.

Fig. 3 is a side view thereof.

I claim:

The ornamental design for a religious shrine, substantially as shown.

ARTHUR VALLIERE.
